Midland, Mich., a corporation of Delaware

Filed Feb. 10, 1964, Ser. No. 343,543

1 Claim. (Cl. 123—41.26)

This invention relates to an improved boiling heat transfer system, and more particularly to improved means for venting of non-condensable gases from such a system.

In systems employing boiling cooling, a common problem exists. Non-condensable gaseous materials such as air, combustion gases, or the like, must be bled from the cooling system periodically to insure proper functioning of the system. In substantially all of the previously proposed methods to solve this problem, substantial quantities of coolant vapor are lost in the bleeding or venting process.

We have discovered an improved means for venting non-condensable gases from boiling cooling systems, whereby loss of coolant is substantially minimized.

Objects and advantages of the present invention will become apparent in the course of the following specification when read in light of the accompanying drawings in which like numbering is used throughout and in which:

FIGURE 1 is a simplified schematic drawing illustrating a boiling cooling system;

FIGURE 2 is a plan view, partially in section, of the coolant storage tank shown in FIGURE 1;

FIGURE 3 is a side elevation of the coolant storage tank taken along line 3—3 of FIGURE 2, showing the tank at reduced coolant level; and

FIGURE 4 is a side elevation of the coolant storage tank taken along line 4—4 of FIGURE 2, showing the tank at maximum coolant level.

In accordance with the present invention, a boiling cooling system for an internal combustion engine 10, comprising a cooling jacket integral with said internal combustion engine and a condenser 11 connected thereto, is provided with a coolant storage tank 12 communicating with said condenser 11 at the portion of said condenser 11 distant from said engine 10 by means of a suitable coolant inlet 14. The coolant storage tank 12 is provided with a coolant inlet 14, a bag vent 15, a tank vent 16, and a collapsible bag 18.

Coolant inlet 14 is positioned in such a manner that coolant enters and leaves from the bottom portion of coolant storage tank 12, regardless of the vertical positional relationship of coolant storage tank 12 relative to condenser 11. Thus, the location of coolant storage tank 12 may be above condenser 11, as shown in FIGURE 1, or may be level with or below condenser 11.

Bag vent 15 is usually a short tube-like communication means between the atmosphere and the interior of collapsible bag 18. Expanded volume of collapsible bag 18 is usually substantially the internal volume of coolant storage tank 12, but may be more or, when storage tank 12 contains coolant under non-operating conditions, less than the internal volume of coolant storage tank 12.

Tank vent 16 communicates between the atmosphere and the interior of coolant storage tank 12 and is provided with a two-position, open-shut valve 19 actuated as by means of a float 20. Float 20 and valve 19 are preferably protected from contact with the collapsible bag 18 by means of a barrier 22, such as a screen, thereby to freely allow the float to follow the coolant level in storage tank 12. For simplicity, and to prevent confusion, barrier 22 is not shown in FIGURES 3 and 4.

Valve 19 is designed to open when float 20 is in the position which corresponds to the coolant level when the

2

engine is not operating as illustrated in FIGURE 3, thereby establishing communication between the atmosphere and the interior of coolant storage tank 12. Valve 19 does not close, then, until float 20 is in the position corresponding to the coolant level under start-up conditions.

In operation, when engine 10 is started, expansion drives coolant through condenser 11 and into coolant storage tank 12. A liquid trap 21 may be employed on condenser 11, if desired, to insure a liquid seal at the end of the condenser 11 nearest coolant storage tank 12. Valve 19 remains open as the coolant level rises, thus expelling non-condensables to the atmosphere through tank vent 16. When the coolant reaches a pre-determined level as illustrated by FIGURE 4, float 20 actuates valve 19, causing valve 19 to close. Fluctuations in coolant level during operation are compensated for by the flow of air into or out of collapsible bag 18. As the coolant level falls, collapsible bag 18 expands and as the coolant level rises, collapsible bag 18 collapses, thereby equalizing the pressure in coolant storage tank 12 with the atmosphere.

When the engine is shut off, the coolant level in coolant storage tank 12 drops to its minimum height, which is never reached while the engine is operating. Float 20, following the level of coolant in storage tank 12, actuates valve 19 and opens tank vent 16 to the atmosphere when a predetermined level is reached. This level is also below the minimum coolant level during operation.

Non-condensable gases work their way to the coolant storage tank 12 and are vented to the atmosphere through tank vent 16 during the periods when valve 19 is in the open position. In this manner, the system is vented only during start up periods when the coolant is at temperatures which are low relative to normal operating temperatures, thus minimizing coolant loss due to vaporization during venting.

Generally, metal would be the preferred material for fabrication of coolant storage tank 12, but any material which is substantially inert to the coolant employed and capable of withstanding temperatures encountered in an ebullient cooling system may be satisfactorily employed.

Collapsible bag 18 is a bag fabricated of material (such as, for example, high temperature resistant pliable rubber, plastics, or the like) which is substantially impervious to air and the coolant employed in the system and is capable of withstanding normal temperatures encountered in operation of the system.

Various modifications may be made in the present invention without departing from the spirit or scope thereof, and it is to be understood that we limit ourselves only as defined in the appended claim.

We claim:

In a boiling cooling system for an internal combustion engine, said system comprising a condenser connected to a cooling jacket integral with said internal combustion engine and containing coolant, the improvement which comprises in combination a coolant storage tank communicating with said condenser by means of a coolant inlet, said coolant storage tank being provided with a bag vent, a tank vent, a collapsible bag within said tank, said collapsible bag connected to said bag vent, said bag vent providing communication between the atmosphere and the interior of said collapsible bag, said tank vent having an open-shut valve attached thereto, said tank vent providing communication between the interior of said coolant storage tank and the atmosphere, said valve having actuation means whereby said valve is opened when the coolant level falls below a predetermined minimum and closes when the coolant level reaches a predetermined maximum.
